(57) CLAIM

I claim the ornamental design for a precut tape with surface ornamentation, as shown and described.

DESCRIPTION

FIG. 1 is a front view of a precut tape with surface ornamentation showing my new design;

FIG. 2 is a side view thereof;

FIG. 3 is a rear view thereof; and,

FIG. 4 is a bottom view thereof.

The broken lines in the drawings depict the boundaries of the claim and form no part thereof.

1 Claim, 4 Drawing Sheets

FIG. 1

FIG. 4

UNITED STATES PATENT AND TRADEMARK OFFICE
CERTIFICATE OF CORRECTION

PATENT NO. : D732,832 S
APPLICATION NO. : 29/469600
DATED : June 30, 2015
INVENTOR(S) : Keith Kusmirek

It is certified that error appears in the above-identified patent and that said Letters Patent is hereby corrected as shown below:

Title page:

In the Drawings:

Delete Drawing sheets 1-4, and replace with Drawing sheets 1-2. (attached)

Signed and Sealed this
Third Day of May, 2016

Michelle K. Lee
Director of the United States Patent and Trademark Office
